[57] CLAIM

The ornamental design for fruit or candy container for floral arrangements, fruit baskets or the like, substantially as shown and described.

DESCRIPTION

FIG. 1 is a top perspective view of a fruit or candy container for floral arrangements, fruit baskets or the like showing my new design;

FIG. 2 is a side elevational view thereof (all elevational views are substantially similar thereto);

FIG. 3 is a sectional view thereof taken on line 3—3 of FIG. 2, the support stick having been omitted;

FIG. 4 is a top plan view thereof; and

FIG. 5 is a bottom plan view of FIG. 3.

FIG. 1.

FIG. 2.

FIG. 3.

FIG. 4.

FIG. 5.
